UNITED STATES PATENT OFFICE

JOHN W. JACKSON, OF FALL RIVER, MASSACHUSETTS

AUTOMATIC CLEANING DEVICE FOR ATOMIZERS

Application filed April 19, 1928. Serial No. 271,227.

The present invention relates to improvements in atomizers for moistening the air in a factory or room wherein the preferred amount or degree of moisture in the air is maintained.

The delivery orifices of such humidifying atomizers are usually small, and at times become clogged or stopped with solid particles.

One of the important objects of the present invention is to provide a means whereby the delivery or discharge orifice can be readily cleared or cleaned out in the event of stoppage.

A further object is to provide a cleaning device for atomizers which will be entirely automatic in its operation, thus saving considerable time and labor, the cleaning device being further at all times positive and efficient in its operation.

20 A further object is to provide an automatic cleaning device for atomizers wherein the cleaning wire normally projects through the discharge orifice or nozzle, a spring pressed head being operatively connected with the cleaning wire so that air under pressure entering the atomizer for commingling with the water will force the spring pressed head inwardly to maintain the cleaning wire in an inoperative position, the wire being automatically moved to an operative position when the air pressure or supply is cut off to the atomizer.

25 A further object is to provide an automatic cleaning device for atomizers of the above mentioned character which is simple in construction, inexpensive, strong and durable and further well adapted to the purpose for which it is designed.

30 Other objects and advantages of the invention will become apparent from the following description when taken in connection with the accompanying drawings.

In the accompanying drawings wherein like reference characters indicate corresponding parts throughout the several views:

35 Figure 1 is a bottom plan view of another for of atomizer having my automatic cleaning device associated therewith, and

40 Figure 2 is a longitudinal sectional view therethrough.

Referring to the drawings there is shown an embodiment of the atomizer wherein the same includes a horizontally disposed air chamber 31 that is open at its respective ends, the central portion of this air chamber being 55 formed with a compressed air inlet 32.

Arranged within the forward end of the compressed air chamber 31 is the water chamber 33, that is closed at its inner end, the forward end thereof being formed with a 60 threaded opening to receive the threaded portion of a conical discharge nozzle 34, and which nozzle terminates in the discharge tube 35. A water inlet pipe 36 extends laterally 65 from the bottom of the inner end portion of the water chamber for communication to any suitable source of water supply.

The cap 37 is detachably secured on the forward end of the air chamber 31 and is spaced with respect to the forward portion 70 of the water chamber 33. The forward end portion of this cap 37 is of conical formation, as illustrated at 38 and terminates in a restricted air discharge nozzle 39 that encircles the water discharge tube 35 formed 75 on the forward end of the nozzle 34.

A cap 40 is removably secured on the open rear end of the air chamber 31 and this cap is formed with a central air vent 41. A partition 42 is provided in the rear end of the 80 air chamber 31 whereby to cooperate with the cap 40 to form a cylinder 43 and this cylinder has communication with the air chamber at 44 in Figure 4. A plunger 45 is arranged for reciprocatory movement in 85 the cylinder 43 and an expansible coil spring 46 is arranged for disposition between the cap 40 and the plunger 45 for normally holding the plunger in forwardmost position in the cylinder.

90 A cleaning rod or wire 47 is secured at its rear or inner end to the plunger 45 and extends through the partition 42 and through the rear end of the water chamber 33, suitable stuffing boxes 48 being provided for the 95 rod on the outer faces of the partition 42 and the rear or inner end of the water chamber. The forward end of the cleaner element projects through the nozzle 34 and the water discharge tube 35 and normally the spring 100

will cause the forward end of the cleaner rod to be extended through the tube.

When air under pressure is admitted to the chamber 31, a certain amount of the air will enter the cylinder 43 to force the plunger 45 rearwardly, compressing the spring 46 and simultaneously moving the cleaning rod 47 rearwardly out of engagement with the tube 35 so that the water entering the chamber 33 through the inlet 36 will be free to be forced through the discharge nozzle and the tube where the same is commingled with the air discharged from the nozzle 39.

As soon as the air pressure is released, the 15. spring 46 will return the plunger 45 and the cleaner rod 47 to the position shown in Figure 4 thus removing any obstruction that may accidentally lodge in the tube 35.

It will thus be seen from the foregoing description that I have provided an automatic 20 cleaning device for association with atomizers for compressed air humidifiers used in mills, plants and the like for humidifying the air and by reason of its simplicity, the cleaning device will at all times be positive and efficient in its operation as well as automatic, thus saving considerable time and labor and expense.

A cleaning device of the above mentioned 30 character can also be readily and easily associated with various types of atomizers without requiring much alterations to the parts of the atomizer with which the cleaning device is to be associated.

35 The automatic cleaning device can be equally as well used on other spraying devices where a fluid under pressure is employed.

While I have shown the preferred embodiment of my invention, it is to be understood 40 that minor changes in the size, shape and arrangement of parts may be resorted to without departing from the spirit of the invention and the scope of the appended claim.

45 Having thus described the invention, what I claim as new and desire to secure by Letters Patent is:—

An atomizer comprising a sectional casing 50 consisting of a centrally disposed tubular section open at its opposite ends and having a central air inlet, a slidable pressure responsive piston in one end of the tubular section, a removable cap section closing the piston end of the central section, a border chamber 55 disposed longitudinally of the opposite end of the said central section and spaced circumferentially from the enclosing wall of said section with its outlet end disposed outwardly of the end of the said section and having a 60 lateral inlet conduit at its inner end formed integral with and projecting exteriorly of the central section, a jet nozzle at the outlet end of said water chamber, a removable nozzle section at the nozzle end of said central 65 section having a cylindrical portion sur-

rounding the said outwardly disposed outlet end of the water chamber, and a conical portion terminating in a restricted nozzle encircling the said jet nozzle of the said chamber, a rod secured at one end to said piston and having its other end disposed in the said jet nozzle in line with the spray orifice thereof and a spring between the said piston and the said removable top section, said spring being tensioned to press against said piston for normally holding said pin in the spray orifice of the said nozzle.

In testimony whereof I affix my signature.

JOHN W. JACKSON.
